[57] ABSTRACT

Related U.S. Application Data

[63] Continuation of Ser. No. 775,386, Nov. 13, 1968,
abandoned.

A protective circuit for a transistor which limits the maximum allowable collector power loss so as to prevent the transistor from being destroyed is disclosed. A second transistor is connected in circuit with the main transistor to control the power loss in the main transistor. In one embodiment the protective transistor has a linear response and in another embodiment the protective circuit has a different slope in different operating ranges.

TRANSISTOR PROTECTIVE CIRCUIT

This application is a continuation of Ser. No. 775,386 filed Nov. 13, 1968 and now abandoned.

BACKGROUND OF THE INVENTION

This invention relates in general to circuits for protecting transistors and in particular to a transistor protective circuit utilizing a current limiter.

DESCRIPTION OF THE PRIOR ART

In transistors the power loss at the collector heats the junctions of the transistors and can destroy the transistors when the temperature exceeds a predetermined value.

The maximum allowable power loss at the collector is substantially constant and when the collector voltage rises in an emitter-grounded transistor, for example, the collector power loss is likely to exceed the maximum permissible value and damage the transistor unless the collector current is decreased. For example, in a transistorized single ended push-pull circuit, commonly referred to as a SEPP circuit, that has its load short-circuited will have only an output coupled capacitor as the load. Such a load will have an impedance close to zero and will be reactive and will shift the phase relationship between the collector voltage and the collector current such that when the collector voltage is at a maximum with respect to a low input, the maximum collector current will flow and will cause the collector power loss to exceed its safe range.

It has been proposed in the prior art to utilize a current limiter for holding the collector current within its desired range even under such conditions. A current limiter serves to hold the collector current below a certain maximum value independent of the collector voltage and under certain conditions holds the collector power loss within a safe range. When an inductive load such as a speaker coil, for example, of about 4 ohms is connected in series to the output coupling capacitor in a SEPP circuit, there is no possibility of introducing a phase shift between the collector voltage and the collector current to insure that the transistor operates even if the collector current exceeds the operating current value of the current limiter. Also, the use of a current limiter limits the maximum output attainable at the load. Also, even if the collector current is lower than the value set by the current limiter, if the collector voltage goes up the collector power loss may exceed its maximum value and result in destruction of the transistor because the current limiter does not prevent such breakage.

SUMMARY OF THE INVENTION

Ideal protection of a transistor is obtained by the use of a current limiter which has a characteristic so that its current limiting value increases when the collector voltage is low and decreases when the collector voltage is high. This means that the operating point of the current limiter must vary with the collector voltage.

It is an object of the present invention to provide a transistor protective circuit which employs a current limiter that varies the limiting level as a function of the voltage applied to the main transistor to be protected. In one embodiment a transistor amplifier is connected with a limiting transistor such that the limiting transistor adjusts the limiting current of the transistor amplifier to prevent injury to the transistor.

BRIEF DESCRIPTION OF THE DRAWINGS

FIG. 1 is a graph illustrating voltage-current characteristic curves for this invention;

FIG. 2 is a schematic view of the invention;

FIG. 3 is a schematic of a modification of the invention;

FIG. 4 is a schematic of a further modification of the invention;

FIG. 5 is a schematic view of a modification of the invention;

FIG. 6 is a schematic view of a modification of the invention;

FIG. 7 is a schematic view of a modification of the invention;

FIG. 8 is a schematic view of a modification of the invention;

FIG. 9 is a schematic view of a modification of the invention;

FIG. 10 is a schematic view of a modification of the invention;

FIG. 11 is a schematic view of a modification of the invention;

FIG. 12 is a schematic view of a modification of the invention; and

FIG. 13 is a schematic view of a modification of the invention illustrating a single-ended push-pull amplifier.

DESCRIPTION OF THE PREFERRED EMBODIMENTS

Various circuits have been proposed for protecting transistors from overload such as the so-called SEPP circuit which employs a current limiting circuit. For example, in FIG. 1 numeral 1 represents a load line, dotted curve 2 represents

the maximum permissible collector power loss (P_c curve). Curve 3 represents a current limiting level. Prior art current limiting circuits are incorporated in SEPP circuits so as to prevent the current from going above the level defined by curve 3 which holds the maximum power loss at P₁ where

curve 3 crosses curve 2. The voltage V_B represents the power source voltage at point P₁ and the voltage at the connection point of the transistors for deriving a load voltage is V_{B/2}. A current limiting circuit holds the output of the SEPP circuit less than a value defined by point P₂ where load curve 1

crosses current limiting level 3. When the collector power loss enters into a range higher than the point P₁, defined by the curves 2 and 3, it is possible that the current limiting circuit will not prevent damage to the transistors.

The present invention prevents damage to a transistor. For example, FIG. 2 illustrates a main transistor T₁ which is to be protected and which is shown as NPN-type transistor, for example. The transistor T₁ has its base connected to an input terminal t_b and has its collector connected to an output terminal

t_c and to a power source terminal t_p through a load resistor R_L. A control transistor T₂ has its collector connected to the base of transistor T₁ and its base is connected to a junction point between resistors R₁ and R₂ that are connected between the collector and emitter of the transistor T₁. The emitter of

transistor T₂ is connected to a terminal t_e which is connected through the resistor R₀ to the emitter of the transistor T₁. The base of the control transistor T₂ is supplied through resistor R₂ a voltage related to the collector current of the main transistor T₁.

During normal operation, the control transistor T₂ is in the off state and does not conduct. However, when the collector power loss of the main transistor T₁ exceeds its given limit range, the control transistor T₂ becomes conductive to control the base current flowing to the transistor T₁ to decrease its collector current, thus protecting the transistor T₁ from damage.

If the collector current and voltage between the collector and emitter of the main transistor T₁ are designated as I_C and V_C, respectively and the voltage between the base and emitter of the control transistor T₂ is designated as V_{BE} it follows that:

$$V_{BE} = (R_2/R_1 + R_2) V_C + R_0 I_C \quad (1)$$

The first term of the right side of this equation represents a voltage related to the collector voltage of the transistor T₁ and the second term represents a voltage related to its collector current, and these voltages are applied to the base of the transistor T₂. Equation 1 can be rewritten as:

$$I_C = \frac{V_{BE}}{R_0} - \frac{R_2}{R_0(R_1 + R_2)} V_C \quad (2)$$

Thus, when the voltage V_C equals zero, a current of V_{BE}/R_0 flows, and the value of the current being controlled decreases as the collector voltage increases with a slope of $R_0/R_0 (R_1 + R_2)$. This is indicated by the straight line 7 of FIG. 1.

Thus, an approximation of the straight line 7 to the curve 2 will increase the working range of the main transistor T_1 . For example, in the case of an SEPP circuit, the main transistor can be driven up to point P_3 where the load curve 1 crosses the straight line so that its output will be increased correspondingly.

If the terminal t_B is connected to the connection point between the base of the main transistor T_1 and the collector of the transistor T_2 , and the terminal t_C is connected to the collector of the transistor T_1 , and the terminal t_E is connected to the connection point between the emitter of the transistor T_2 and the resistor R_0 and if the terminals t_B , t_C and t_E are considered as analogous to the base, collector and emitter electrodes of a transistor, the protective circuit may be applied to other transistor circuits.

Although the current limiting effect is produced by the straight line 7 which approximates the permissible collector power loss curve 2 by the circuitry of FIG. 2, a more accurate approximation may be made by a line having two parts with different slopes. Such a characteristic is obtained with the circuit of FIG. 3. In FIG. 3, elements similar to those in FIG. 2 are identified by the same reference numerals and characters. A resistor R_3 is connected between terminal t_C and the resistor R_1 , and the resistor R_4 and the diode 10, such as a Zener diode, is connected between the emitter of transistor T_1 and the junction point between resistors R_1 and R_3 .

In the circuit of FIG. 3, when the voltage between the collector and emitter of the main transistor T_1 is low, the Zener diode 10 will stay in the off state and the circuit will operate similar to the circuit of FIG. 2. In other words, the collector current I_C decreases relatively abruptly with an increase in the collector-emitter voltage V_C . When the collector voltage V_C exceeds a certain value, the Zener diode 10 will become conductive due to the Zener effect and a constant voltage will be applied to the base of the control transistor T_2 and at the same time a voltage related to the collector current I_C will be fed to the base of the transistor T_2 . In this range the collector voltage-current characteristics of the main transistor T_1 will have a relatively general slope. If the voltage across the Zener diode 10 is designated as V_Z , when:

$$V_C < \frac{V_Z}{R_1 + R_2}, \quad (3)$$

it follows that:

$$I_C = \frac{V_{BE}}{R_0} - \frac{R_2}{R_0} \cdot \frac{V_C}{R_1 + R_2 + R_3} \quad (4)$$

when:

$$V_C > \frac{V_Z}{R_1 + R_2}, \quad (5)$$

it follows that:

$$I_C = \frac{V_{BE}}{R_0} - \frac{R_2}{R_0} \cdot \frac{R_3}{R_4} \cdot \frac{V_Z}{R_3 (R_1 + R_2) + R_1 + R_2 + R_3} - \frac{R_2}{R_0} \cdot \frac{V_C}{R_3 (R_1 + R_2) + R_1 + R_2 + R_3} \quad (6)$$

This is illustrated as curve 11 in FIG. 1 which has two parts. Thus, when the collector voltage V_C is low, the curve 11 has a

relatively steep slope but when the collector voltage V_C is above a value of

$$\frac{R_1 + R_2 + R_3}{R_1 + R_2} V_Z$$

the curve takes on a gentler slope close to curve 2.

FIG. 4 illustrates a modification of the circuit of FIG. 2 in which a diode 12 is connected between the base of the transistor T_1 and the collector of the transistor T_2 . The diode 12 will prevent current from flowing from the base of the transistor T_2 to the collector when the main transistor T_1 is non-conductive.

The diode 12 may be replaced with a third transistor T_3 as shown in FIG. 5 to prevent the unwanted conduction of the transistor T_2 and the composite h_{FE} of the transistors T_2 and T_3 rises to provide for improved control efficiency.

FIG. 6 illustrates a further modification wherein a fourth transistor T_4 is connected in circuit with the transistor T_1 to provide a Darlington connection. FIG. 7 illustrates transistors T_1' and T_4 which are of different conductivity types connected in a Darlington circuit.

FIGS. 8 through 12 are the equivalent circuits PNP-type transistors instead of the NPN-types illustrated in FIGS. 2 and 4-7. For example, the circuit in FIG. 8 has transistors T_1' and T_2' which are PNP-types and the circuit operates as the circuit of FIG. 2. The circuit of FIG. 9 corresponds to the circuit of FIG. 4 except the transistors T_1' and T_2' are PNP-types. The circuit of FIG. 10 corresponds to the circuit of FIG. 5 except the transistors T_1' , T_2' and T_3' are PNP-types instead of NPN's.

The circuit of FIG. 12 corresponds to the circuit of FIG. 7 except the types of the transistors T_1' through T_4' are different types than in FIG. 7.

FIG. 13 illustrates a semi-complementary SEPP circuit which has transistors T_5 , T_6 , T_7 and T_8 where the NPN-type transistor T_7 and the PNP-type transistor T_8 are respectively, connected to the NPN-type transistors T_5 and T_6 . The transistors T_7 and T_8 are driven by a common driving transistor T_9 . The driving transistor T_9 is connected to a power supply terminal 15 through a bias supply comprising the diodes 13 and a resistor R_4 . An input terminal 16i is connected to the base of transistor T_9 and an output terminal 16o is coupled through a capacitor 17 to the collector of the transistor T_{11} . The transistor T_{10} is connected as a control transistor for the transistor T_7 . A resistor R_{11} is connected to the connection point between the transistors T_5 and T_6 and the capacitor 17. A pair of voltage dividing resistors R_6 and R_8 are connected across the resistor R_{11} . The emitter of transistor T_{12} is connected to the connection point between resistors R_5 and R_6 . The collector of the transistor T_{10} is connected to the base of transistor T_7 through a diode 20 connected in a forward direction relative to the transistor T_{10} .

A pair of resistors R_7 and R_8 are connected between the connection point between transistors T_5 and T_6 and the power supply terminal 15. The junction point between resistors R_7 and R_8 is connected to the base of the transistor T_{10} . A transistor T_{11} is connected to protect the transistor T_8 and the emitter of the transistor T_{11} is connected to the base of the transistor T_8 and its collector is connected to the connection point between the capacitor 17 and the resistor R_{11} .

The base of the transistor T_{11} is connected to the collector of a transistor T_{12} which has its emitter connected to the connection point between resistors R_5 and R_6 . The base of transistor T_{12} is connected to the connection point of resistors R_9 and R_{10} which are connected from the connection point of the transistors T_5 and T_6 and ground. In the circuit of FIG. 13 when either of the transistors T_7 and T_8 is conductive the other is non-conductive and a reverse voltage is applied between the base and emitter of the non-conductive transistor. The diode 20 is connected in series with the protective control transistor T_{10} or the transistor T_{12} of opposite polarity to transistor T_{11} is connected to the transistor T_{10} to prevent lowering of the input impedance. The voltage dividing resistors R_6 and R_8

which are connected in parallel with resistor R_{11} correspond to resistor R_o in FIG. 2 and a voltage is produced across the resistor R_{11} which is fed to the transistors T_{10} and T_{11} .

The protective circuit of this invention allows the efficient use of transistors and eliminates the destruction of transistors due to overload. Apparatus according to this invention has been constructed and tested and the output of an amplifier which previously produced 50W was safely raised to a level of 100W by the use of the invention described herein.

It will be apparent that many modifications and variations may be effected without departing from the scope of the novel concepts of this invention.

I claim as my invention:

1. A protective circuit for protecting a main transistor which receives an input signal on its base from an input terminal comprising:
  - a unilateral current device;
  - a second transistor connected with its emitter and collector in series with the unilateral current device between the base of the main transistor and an output terminal;
  - three resistors connected in series between the collector and emitter of the main transistor and developing a voltage proportional to the voltage between the emitter and collector of the main transistor;
  - the base of the second transistor connected to the junction point between the one of said three resistors connected to the collector of said main transistor and the second of said three resistors to receive a signal indicative of the voltage between the emitter and collector of the main transistor;

a fourth resistor connected to the emitter of said second transistor and to the junction point between said second and third resistors so as to supply a voltage proportional to the collector current of the main transistor to the second transistor such that when the voltage between the collector and emitter of the main transistor is low the collector voltage versus current characteristic of the main transistor will have a relatively steep slope and when the collector voltage exceeds a predetermined value the collector voltage versus current characteristic of the main transistor will have a relatively gentle slope.

2. A protective circuit according to claim 1 comprising a fifth resistor connected between the emitter of said second transistor and said output terminal.

15 3. A protective circuit according to claim 2 including a third transistor with its base connected to the emitter of said main transistor and its collector connected to the collector of said main transistor and a sixth resistor connected between the emitter of said third transistor and the junction point between 20 said second and third resistors.

4. A protective circuit according to claim 3 including a fourth transistor of opposite type to said main transistor receiving said input signal on its base from said input terminal, seventh and eighth resistors connected in series between the

25 emitter of said fourth transistor and said output terminal, a fifth transistor with its collector connected to said output terminal and its emitter connected to the base of said fourth transistor, and the base of said fifth transistor connected to the junction point between said seventh and eighth resistors.
